DESIGN FOR A UNIFORM

Arthur M. Berger, New York, N. Y.

Application September 14, 1940, Serial No. 95,033

Term of patent 3½ years

To all whom it may concern:

Be it known that I, Arthur M. Berger, a citizen of the United States of America, residing in the city of New York, county of New York, and State of New York, have invented a new, original, and ornamental Design for a Uniform, of which the following is a specification, reference being had to the accompanying drawing, forming part thereof.

Fig. 1 is a front view of a uniform showing my new design.

Fig. 2 is a rear view thereof.

Fig. 3 is a fragmentary view of Fig. 1 with the bib portion removed.

I claim:

The ornamental design for a uniform, substantially as shown and described.

ARTHUR M. BERGER.
